SHUTTLE CHECK, PICKING MECHANISM,
AND PARALLEL MOTION FOR LOOMS

George Crompton, Jr., Framingham, Mass.

Application October 8, 1948, Serial No. 53,532

17 Claims. (Cl. 139—150)

1

This invention relates to the picking mechanism of fly shuttle looms, particularly single shuttle looms, but may be also applied at the single box end of drop box looms and may be further applied to the drop box end of drop box looms which have a single box at the other end. Thus the invention may be used on 1 x 1 looms for both boxes, on 2 x 1, 4 x 1 and 6 x 1 looms at the single box end and even in certain cases at the drop box end.

One object of the invention is to provide a smoother acting loom to the end that, vibration being lessened, the warp and filling breakage will be less for a given speed in picks per minute. Another object of the invention is the attainment of greater speed as measured by picks per minute without paying a penalty in the form of greater warp breakage or greater filling breakage. Another object of the invention is so to smooth the picking action as to lower the filling breakages. Another object of the invention is so to smooth the picking action as materially to reduce shuttle rebound which, in automatic looms, is a detriment, resulting in loom stoppage and the necessity of adjustment. Another object of the invention is to reduce knocking off (banging off). Another object is to render the adjustment of the boxes (that is, the binders thereof) less critical which will save many man hours in the setting up and operation of looms. Another object is to make a loom independent of conditions of humidity so far as mechanical functioning is concerned. Another object is to permit the entire dispensing with the binder springs for the boxes of looms.

Another object of the invention is to improve the Recoil Picking Mechanism for Looms patented in my expired U. S. Patent #1,393,758, dated Oct. 18, 1921. Another object of the invention is to provide a mechanism of the class indicated which will operate year in and year out without failure. Another object is to provide a mechanism of the class indicated which will check the shuttle with a strong force as it comes into the box but which will not tend to make the shuttle rebound, all with such a simple mechanical arrangement as renders breakdown unlikely. Another object is to provide a fool-proof check which starts to operate the moment the shuttle starts entry into the box, entirely independent of the binder and which reduces rebound instead of increasing it. Another object of the invention is to provide a thoroughly satisfactory mechanism for operating the picker sticks so that, after picking, they stay forward

2

instead of being retracted by a parallel motion spring, whereby such picker sticks help to stop the shuttle by their own inertia.

Another object of the invention is to reduce the amount of power required to operate a loom, which may seem insignificant in terms of one loom per one day but which becomes significant as measured by one thousand looms per year. Another object is to make looms distinctly quieter which offhand may not seem of much importance but which, in terms of strain on human persons, is actually of the greatest importance. Another object is to cause the bobbin changing mechanism of an automatic loom to function more accurately with fewer breakdowns. Another object is to cause the feeler mechanism of an automatic loom to function more accurately.

Other objects will be in part obvious or in part pointed out hereinafter. The invention accordingly consists in the features of construction, combinations of elements, and arrangements of parts, all as will be illustratively described herein, and the scope of the application of which will be indicated in the following claims.

25 In the accompanying drawings illustrating one of many possible embodiments of the mechanical features of this invention:

Figure 1 is a side elevation of a shuttle check picking mechanism and parallel motion for looms constructed in accordance with the invention;

Figure 2 is a vertical sectional view taken on the line 2—2 of Figure 3;

Figure 3 is a vertical sectional view taken on the line 3—3 of Figure 1;

Figure 4 is a fragmentary sectional view taken on the line 4—4 of Figure 1.

Referring first to Figure 2, I provide a plate member 10 which is substantially a rectangular parallelopiped with a shaped slot 11 and with an enlarged end portion 12 having a bore 13 whereby it may be mounted in the end of the rock shaft of a loom and secured in place by a set screw 14 equipped with a check nut 15. The slot 11 widens in an expanding curve from top to bottom on each side in sections parallel to the plane of the picker stick. The plate member 10 should be of metal of low permeability (high reluctance) in a magnetic circuit. In other words, it should be of non-ferrous metal and, all things considered, the brasses and the bronzes are probably the best alloys for the purpose, as they have adequate strength.

Referring now to Figures 1 and 3, I provide a pair of permanent magnets 16 and 17 which have

the shape of rectangular parallelopipeds, the top surfaces of which are flush with the top surface of the plate member 10, thus to form a wide horizontal plane surface 18 broken by the slot 11. These magnets 16 and 17 are mechanically part of the parallel motion plate. The magnets 16 and 17 are thicker in the vertical dimension than the plate member 10, so therefore the magnets 16 and 17 extend below the plate member 10, as clearly shown in Figure 3.

Under the plate member 10 and between the magnets 16 and 17 is a yoke member 20, which is also a rectangular parallelopiped having the same length as the plate member 10 and the magnets 16 and 17, the same width as the plate member 10 and a thickness equal to the difference between that of the magnets 16 and 17 and that of the plate member 10. The plate member 10, the magnets 16 and 17 and the yoke member 20 thus together form a horseshoe magnet in the shape of a rectangular parallelopiped with opposite poles on the top surface 18, as indicated. The entire assembly is held together with four brass screws 21 and nuts 22.

The magnets 16 and 17 are of some highly magnetizable material, naturally a ferrous metal or alloy, and the best material for the purpose known to me is an alloy of iron, aluminum, nickel and cobalt, which is now well known and readily available. It is capable of being magnetized to a high magneto-motive force H . The magnetic axes of the magnets 16 and 17 should be vertical so that the poles are on top and on the bottom, and it has been found to be quite possible to magnetize rectangular parallelopipeds so that the magnetic axes are along a shorter dimension. The top surface 18 of one magnet should be of opposite polarity to that of the top surface 18 of the other magnet, as indicated by the symbols N and S in Figure 3, but whether the north pole is on the right or left is quite immaterial.

The yoke 20 should be of highly permeable material and the best such material known to me is soft steel, of low carbon content. The holding power of the entire magnetic system is a function of the flux B , where $B = MuH$ and Mu is the permeability of the entire system. The function of the yoke 20 is to transmit the flux from one bottom pole to the other bottom pole so therefore it should be as permeable as possible.

The picker stick is indicated at 25, only the lower portion being shown, since it will be operated by the customary picking cam and roll or ball and shoe and lug strap and have a rawhide picker as is customary. A spindle mounted picker is not precluded. Preferably, the picker stick 25 is made of wood as indicated.

As clearly illustrated in Figures 1, 2 and 3, the picker stick 25 is mounted in a shoe-rocker 26 at least the lower part of which is made of highly permeable material such as soft iron or soft steel. This shoe-rocker constitutes the armature in the magnetic circuit. It has an arcuate bottom surface 27 such that the picking point will travel in a straight line, as is known. By the line contact of the shoe-rocker with the magnetic surface 18, the shoe-rocker 26 is strongly held to the assembly of magnets 16 and 17 and thus the parallel motion spring may be dispensed with.

Integral with the shoe-rocker 26 and extending downwardly from the bottom thereof is a tongue 30 which however should be made of non-permeable material such as brass or bronze and may be brazed to the bottom of the shoe-rocker

26. The relative shapes of the slot 11 and the tongue 30 in an illustrative embodiment of this invention are clearly shown in Figure 2 and so also are the clearances. These shapes and clearances are such that in no position of the parts will they bind and furthermore so that when the powerful thrust of the lug strap drives the picker stick forward, there will be no resultant force tending to raise the shoe-rocker 26 from the surface 18 and also when the shuttle is being checked there will be no resultant upward force.

The shoe-rocker 26 has an upstanding portion 35 which has a rectangular parallelopipetal recess 36 to receive the lower end of the picker stick 25 which is locked in position by a lock screw 37 assisted by a check nut 38. In the drawings, the picker stick 25 and the shoe-rocker 26 are shown in the mid position which they occupy only momentarily, it being understood that at the start of the pick the picker stick 25 is at an acute angle to the righthand side of the surface 18, Figure 1, and at the end of the picking motion the picker stick 25 is at an acute angle to the lefthand side of the surface 18, Figure 1. It will be seen that, as thus far described, there is nothing to withdraw the picker stick 25 after it has thrown the shuttle and therefore it stays forward, but nevertheless it is firmly held from rising by the magnetic attraction. The inertia alone of the picker stick 25 as well as of the shoe-rocker 26 and the upstanding portion 35 constitutes a powerful check to stop the shuttle when next it returns into the box but without setting up any force which can help to cause a rebound, for the shoe-rocker 26 is held to the surface 18 without any tendency to move the picker stick 25 forward or back.

However, I preferably provide magnetic means tending to hold the picker stick 25 in the forward position to which it is thrust by the picking motion by means of the lug strap. This may take the form of an additional armature 40 having plane bottom surfaces 41 which will make area (instead of line) contact with the surface 18 of the magnets 16 and 17. The armature 40 has in the bottom thereof as shown in Figure 4 a groove 42 of a width equal to the width of the plate 10 and in this groove 42 is an armature holding member 43 made of material of low permeability such as brass or bronze. The armature holding member 43 may be brazed to the main portion of the shoe-rocker 26 and a front portion 26a thereof, thus bridging and connecting these portions. These portions are also connected by an upper connecting piece 44 having a strengthening rib 45 which may be made of any metal that can be securely attached, as by brazing, to the main portion of the shoe-rocker 26 and its front portion 26a.

It will be seen that the armature 40 is held loosely in position so that its flat bottom surfaces can seat tightly upon the surface 18 of the magnets 16 and 17 throughout a fairly wide range of angular positions of the picker stick 25 as the picking stroke ends. Thus, rebound of the picker stick from its forward position can take place without disturbing the grip upon the armature 40 by the magnets 16 and 17 which hold the armature 40 with a powerful force due to the large area of contact. Thus additional checking means is provided when the incoming shuttle breaks loose the armature 40 from the magnets 16 and 17 and furthermore the attraction of the magnets 16 and 17 for the armature

48 actually returns energy to the next picking stroke.

Whenever possible, a loom should be equipped with two of the mechanisms of this invention, one for each picker stick mounted on the ends of the rock shaft. Looms so equipped will run with less vibration, less noise and less power and may be run at higher speed and will otherwise accomplish the objects of this invention. The boxes may be much looser than ordinarily and it is picking a shuttle out of a tight box that holds down the overall performance of a loom. While electro-magnets might be used in place of permanent magnets, the latter are more convenient and require no wiring.

The usual lug strap permits the picker stick to remain forward after the picking shaft has returned to the position where it is ready to make another pick. However, if in some cases the lost motion is not sufficient, the lug strap should be adjusted or a new one selected that will provide sufficient lost motion. The connection of the lug strap to the picker stick should be high enough so that the picking motion will not tend to lift the picker stick.

The tongue 30 and slot 11 are shaped so as to take the reaction of picking as well as the reaction of checking. During the picking, force is applied to the picker stick 25 by the lug strap and this meets the resistance of the shuttle due to inertia and to the friction of the binder. The picker stick 25 thus becomes a lever and the tongue 30 is urged powerfully to the left, Figure 2. The plate 10 takes the thrust and, by reason of the shapes of the tongue 30 and slot 11, there is no resultant tending to lift the picker stick 25. When the shuttle is being checked there is at first a thrust to move the top of the picker stick 25 to the right and a holding force due to the attraction of the armature 40. Thus results in a downward component of force on the picker stick 25. Later the fulcrum becomes the center of gravity of the whole system of picker stick 25, shoe-rocker 26 and the upstanding portion 35, resulting in a force to drive the tongue 30 to the right, Figure 2. This is taken by the engagement of the righthand side of the tongue 30 with the wall of the slot 11, again without any resultant upward force on the picker stick 25 due to the shapes of the parts. There will be a slight sliding back and forth of the shoe-rocker 26 in the surface 18 so the surface 18 should be greased to prevent or reduce wear.

Since permanent magnets readily pick up nuts, screws, tools, iron filings, etc. that may be dropped near them, it will be best to secure high brass plates with inturned edges to the sides of the magnets 16 and 17 forming a sort of box for the mechanism but these have not been shown in the drawings as they would obscure the other parts.

The tongue 30 besides having the functions already described serves to align the shoe-rocker 26 upon the plate member 10, that is to say, it keeps the plane of the picker stick 25 in line with or parallel to the fell of the cloth being woven or it keeps the plane of the picker stick 25 in line with or parallel to the intended line of flight of the shuttle. But since clearance between the tongue 30 and the magnets 16 and 17 should be provided to prevent binding, the yoke 30 should be a few thousandths of an inch thicker than the tongue 30.

It is desirable that as the parts wear, the shoe-rocker 26 should still make line contact with

the magnets 16 and 17. So therefore the plate member 10 should wear as fast as the magnets 16 and 17. Bronzes having about 20% of tin, the rest copper, are friable and this or a strong but soft alloy may be used for the plate member 10. On the other hand, the plate member 10 may be reduced in height so that its top surface is below that of the magnets 16 and 17.

The member 10 as well as the assembly of member 10 and the magnets 16 and 17 is called a "plate" because this is the conventional name of the supporting member of the conventional parallel motion. It will be seen that the magnets 16 and 17 can readily be removed for re-magnetization or replacement and can as easily be resecured.

It will thus be seen that there has been provided by this invention an apparatus according to which the various objects hereinabove set forth together with many thoroughly practical advantages are successfully achieved. As many possible embodiments may be made of the mechanical features of this invention, and as the embodiment above described may be varied in various parts, all without departing from the scope of the invention, it will be understood that all matter hereinbefore set forth is to be interpreted as illustrative and not in a limiting sense.

I claim:

30 1. Apparatus of the class described comprising a shoe-rocker for a picker stick which shoe rocker is made of magnetically permeable material, a plate to support said shoe-rocker, and magnetic means to hold said shoe-rocker upon said plate.

35 2. Apparatus of the class described comprising a shoe-rocker for a picker stick which shoe rocker is made of magnetically permeable material, and magnetic means to hold said shoe-rocker in position and to resist retrograde movement of the picker stick.

40 3. Apparatus of the class described comprising a magnetic parallel motion plate, a magnetically permeable shoe-rocker having a curved bottom surface, and a portion of said shoe-rocker having a recess to hold a picker stick.

45 4. Apparatus of the class described comprising a magnetic parallel motion plate, a magnetically permeable shoe-rocker having a curved bottom surface, a portion of said shoe-rocker having a recess to hold a picker stick, there being a slot in the plate said slot widening in an expanding curve from top to bottom on each side in sections parallel to the plane of the picker stick, and a tongue in the slot to take thrust in both horizontal directions, the tongue and slot being so shaped as to avoid resultant force which would lift the shoe-rocker from the plate in opposition to the magnetic attraction.

50 5. Apparatus of the class described comprising a magnetic parallel motion plate, a magnetically permeable shoe-rocker having a curved bottom surface, a portion of said shoe-rocker having a recess to hold a picker stick, and an armature connected to said shoe-rocker, said armature having a bottom surface shaped to make area contact with said plate whereby said shoe-rocker is magnetically held to said plate in all angular positions and is strongly held on said plate to a particular angular position in which position it checks the incoming shuttle.

55 6. Apparatus of the class described comprising a magnetic parallel motion plate, a magnetically permeable shoe-rocker having a curved bottom surface, a portion of said shoe-rocker having a

recess to hold a picker stick, an armature connected to said shoe-rocker, said armature having a bottom surface shaped to make area contact with said plate whereby said shoe-rocker is magnetically held to said plate in all angular positions and is strongly held on said plate to a particular angular position in which position it checks the incoming shuttle, there being a slot in the plate said slot widening in an expanding curve from top to bottom on each side in sections parallel to the plane of the picker stick, and a tongue in the slot to take thrust in both horizontal directions, the tongue and slot being so shaped as to avoid resultant force which would lift the shoe-rocker from the plate in opposition to the magnetic attraction. 15

7. Apparatus as claimed in claim 1, in which the magnetic means is a horseshoe type permanent magnet.

8. Apparatus as claimed in claim 2, in which the magnetic means is a horseshoe type permanent magnet.

9. Apparatus as claimed in claim 3, in which the parallel motion plate includes a horseshoe magnet, the magnetic axes of which are substantially perpendicular to the plate surface. 25

10. Apparatus as claimed in claim 4, in which the parallel motion plate includes a horseshoe magnet, the magnetic axes of which are substantially perpendicular to the plate surface. 30

11. Apparatus as claimed in claim 5, in which the parallel motion plate includes a horseshoe magnet, the magnetic axes of which are substantially perpendicular to the plate surface.

12. Apparatus as claimed in claim 6, in which the parallel motion plate includes a horseshoe magnet, the magnetic axes of which are substantially perpendicular to the plate surface. 35

13. Apparatus of the class described comprising a picker stick holder, a parallel motion for said picker stick holder, and a magnet to hold the holder in a given angular position on the parallel motion until the inertia of a shuttle striking the picker stick breaks the hold of the magnet on the holder. 40

45

14. Apparatus of the class described comprising a picker stick holder, a separate loom part, a magnet and an armature to be held by the magnet, one of said last two parts being secured to the holder and the other to the separate loom part whereby the picker stick holder may be held in a given angular position until the inertia of a shuttle striking the picker stick breaks the hold of the magnet on the armature.

15. Apparatus as claimed in claim 14, in which the magnet is a permanent magnet.

16. Apparatus of the class described comprising a parallel motion having two main parts, one of said parts being a supporting plate and the other of said parts being a rocker, one of said parts being a magnet and the other of said parts being magnetically permeable to be attracted by said magnet.

17. Apparatus of the class described comprising a parallel motion plate, a shoe-rocker fitting said plate, a magnet and an armature, one of said last two parts being on the plate and the other on the shoe-rocker, and the magnet and the armature being so positioned on the plate and the shoe-rocker that they hold the shoe-rocker in an extreme angular position on the plate in order to check a shuttle the inertia of which breaks the hold of the magnet on the armature.
